LOUIS COATALEN, OF WOLVERHAMPTON, ENGLAND, ASSIGNOR OF ONE-HALF TO
SUNBEAM MOTOR CAR COMPANY LIMITED, OF WOLVERHAMPTON, ENGLAND.

FUEL-FEED SYSTEM FOR AERIAL MACHINES.

1,299,128.

Specification of Letters Patent.

Patented Apr. 1, 1919.

Application filed May 23, 1917. Serial No. 170,539.

To all whom it may concern:

Be it known that I, LOUIS COATALEN, a subject of the King of England, residing in Wolverhampton, Staffordshire, England, have invented certain new and useful Improvements in Fuel-Feed Systems for Aerial Machines, of which the following is a specification.

On aeroplanes which are used for military and naval purposes it is very important that the petrol feed should not be interrupted should the petrol tank be hit, and it is the object of the present invention to provide simple means for enabling a supply to be maintained for a certain period even though the main tank is punctured.

Usually the petrol supply is split up, a number of tanks being used, and in most cases the engine draws from one tank, hereinafter termed the subsidiary tank, which is supplied automatically from the main tanks. In some cases the main tanks are under pressure, but this is objectionable because should one of the main tanks become slightly damaged or punctured by shot, the pressure supply ceases. It is not possible in all cases to locate the main tanks above the subsidiary tank and so obtain gravity feed.

A further system which might seem practical is that in which the subsidiary tank contains float operated mechanism, and is connected with the engine inlet pipe so that the depression in the inlet pipe causes the fuel to be sucked up from the main tank to the subsidiary tank. This system is not, however, practicable in the case of an aeroplane engine because generally there is little or no depression in the inlet pipe.

According to this invention, a subsidiary tank is employed with float-controlled valve mechanism of the kind mentioned, and the depression is caused to be generated by a suction pump driven by a small vane wheel so that motion through the air causes the pump to operate and therefore the depression is maintained even though the engine is at rest.

It has been proposed hitherto to furnish

the carbureter of an aeroplane engine with a fuel pump driven by a vane wheel, but the present invention consists, as above stated, in the combination of a pump of this kind with a subsidiary tank and float operated mechanism.

The accompanying drawings show diagrammatically how the invention may be carried into effect.

The main tank, A supplies fuel by means of the pipe B to the upper chamber C of the subsidiary tank. The lower chamber D of this supplies the carbureter through the outlet pipe E, and the pipe F is a suction pipe connected to an air pump G carrying a vane wheel H. In the top of the main tank A is an air vent J which may be a spring-seated valve.

As the vane wheel H rotates suction is generated in the chamber C causing fuel to be drawn along the pipe B and into the chamber. The float K gradually rises, meantime fuel passes through into the lower tank D and then to the carbureter. This mechanism is not described in detail because in itself it forms no part of the invention, and its operation is well known.

By the present invention it is possible to employ two tanks with automatic feed from the main tank to the subsidiary one without employing pressure or requiring any attention on the part of the operator. Thus should the main tank be damaged the machine can travel a considerable distance on the supply in the subsidiary tank.

What I claim as my invention and desire to secure by Letters Patent is:—

1. In a fuel feed system for aerial machines, a subsidiary tank adapted to feed a carbureter, a main tank supplying the subsidiary tank, float operated mechanism in the subsidiary tank, a vane wheel and a suction pump driven thereby and connected to the float operated mechanism.

2. In a fuel feed system for aerial machines, a main tank, a subsidiary tank, a pipe connecting the main and subsidiary tanks, a float operated mechanism within

the subsidiary tank, a pipe leading from the subsidiary tank to a carbureter, a vane wheel, a suction pump operated thereby, a pipe connected to the pump and controlled by the float operated mechanism and an air vent also controlled by the float operated mechanism.

In testimony whereof I have signed my name to this specification in the presence of two subscribing witnesses.

LOUIS COATALEN.
